UNITED STATES PATENT OFFICE.

JAMES S. HARKINS, OF MINNEAPOLIS, MINNESOTA, ASSIGNOR OF ONE-HALF
TO JACOB MERRITT, OF SAME PLACE.

BOILER-FURNACE.

SPECIFICATION forming part of Letters Patent No. 425,072, dated April 8, 1890.

Application filed January 27, 1890. Serial No. 338,214. (No model.)

To all whom it may concern:

Be it known that I, JAMES S. HARKINS, of Minneapolis, in the county of Hennepin and State of Minnesota, have invented certain new and useful Improvements in Boiler-Furnaces, of which the following is a specification.

The object of my invention is to provide a furnace for generating heat which will by means of its construction and the combination of its several parts consume the fuel more perfectly, and at the same time obviate the use of what is commonly termed a "smoke-consumer," thereby utilizing to the fullest extent the heating properties of the fuel.

15 In the accompanying drawings, forming a part of this specification, Figure 1 is a longitudinal vertical section of a boiler and furnace embodying my improvements. Fig. 2 is a front elevation and partial vertical section of the same on line *y y* of Fig. 1. Fig. 3 is a horizontal section on line *x x* of Fig. 1.

In the drawings, 2 represents the outer or supporting wall; 3, a cross-wall forming the rear of the ash-pit 4.

25 5 represents a boiler supported upon the walls 3, having the smoke-flue 7 and the head-opening 8, leading into the exit-flue 9. The front plate 10 is provided with the door 11, leading to the smoke-flue 7 of the boiler for 30 cleaning-out purposes, the fuel-door 13 for the admission of fuel, and the ash-door 15 for removing the ashes from the ash-pit 4. In the ash-door 15 are arranged draft-openings 17 for the admission of air to the fire-box 35 through the grate-bars 18, a sliding damper 20 being arranged over the draft-openings 17 for regulating the admission of air through said openings.

40 Directly under the front end of the boiler 5 is arranged the fire-pot 23, having the double walls 25 and 26 on each side, and the rear preferably formed U-shaped, the top being fitted up against the bottom of the boiler 5 on each side, while the rear portion 27 and 45 28 is only carried up part way to the boiler, leaving an open space 51 from said fire-pot back under the boiler, which may be closed by the dampers 50. The rear wall 27 and 28 of the fire-pot is preferably set on an incline 50 toward the back part of the furnace. The

inside walls 25 and 27 are preferably corrugated, as shown in Fig. 3. An inner lining of fire-clay 30, corrugated to register with the corrugations on the walls 25 and 27, is so arranged as to form a number of openings or 55 diving-flues 19 from the fire-box down on the outside of the lining 30, and the inner walls 25 and 27, leading to the main exit-flue 33, formed by the rear wall 28 and the bottom of the boiler 5 and the ground 34 beneath, 60 said flue being preferably lined with fire-brick 35, or other suitable material.

In the front plate 10 are openings 37, leading into the opening 38 in the walls of the fire-pot. The inner walls 25 on the side and 65 the walls 27 and 28 in the rear are provided with a series of holes 39 for the admission of air through the openings in the walls into the fire-pot and through into the smoke-flue 33.

Leading from the steam-dome of the boiler 70 or other suitable steam-receptacle is a steam-pipe 40, which is preferably placed in the hollow wall of the fire-pot, from which the end projects into the fire-pot for the admission of steam into the same to facilitate the combustion 75 of the gases before they have escaped from the fire-pot.

The operation is as follows: Fuel being placed in the fire-pot 23 through the door 13, it is ignited in the usual manner, the damper 8c 50 being thrown down and back, so as to make a direct draft to aid in starting the fire. The air coming in through the openings in the ash-door 15 rushes up through the grate-bars, and the fuel thereon supplying the necessary 85 oxygen for the purpose of starting the fire, the smoke and unconsumed gases passing out through the opening 51 into the smoke-flue 33. When the fire is sufficiently started, the damper 50 is closed, forcing the gases and 90 products of combustion to find exit either through the openings between the corrugations of the inner lining 30 and the inner walls 25 and 27 or back through the fuel and out into the smoke-flue 33 in the direction of 95 the arrows. The air, being admitted through the hollow walls of the fire-pot, enters through the openings 39, furnishing an additional supply of air to the rising gases, which are drawn down, ignited, and are carried off in the usual 100

manner into the smoke-flue 33, thence through the boiler-flues 7, and out of the exit-flue 9. The fuel being supplied with a sufficient amount of oxygen is always alive, and the 5 gases which naturally arise from the fuel during combustion are carried directly through the fuel and into the smoke-flue 33, whether the current be directly toward the flue 33 or by way of the corrugated channels as they 10 terminate above the grate-bars 18.

I claim as my invention—

1. The combination, in a furnace, of a fire-pot having its walls formed hollow and connected to the outer air and provided with a 15 series of openings leading from the hollow wall into the fire-pot, a corrugated inner lining forming diving-flues, with similar corrugations on the inner wall of said fire-pot, the grate-bars 18, and the smoke-flue 33, substantially as described, and for the purpose specified.

2. The combination, in a furnace, of a fire-pot, an inclosing hollow wall, a series of openings from said hollow wall into said fire-pot, 25 openings leading into said hollow wall from the outer air, a steam-pipe adapted to deliver a spray of steam in said fire-pot, and the draft-openings 17, grate-bars 18, and smoke-flue 33, substantially as described.

3. The combination, in a furnace, of the 30 fire-box 23, having the walls 25 and 26 on the

sides formed U-shaped, the walls 27 and 28 at the rear formed U-shaped and of a less height than the side walls, and said walls being closed at the top, forming a hollow space 35 between them, said hollow space being connected by suitable openings with the outer air and by a series of holes with the fire-pot 23, the damper 50, and the smoke-flue 33, substantially as described.

4. The combination, in a furnace, of the fire-pot 23, having the side walls 25 and 26 and the rear walls 27 and 28, provided with the openings 39, a corrugated lining 30, forming with similar corrugations on the walls 25 45 and 27, diving-flues, the grate-bars 18, damper 50, and smoke-flue 33, substantially as described, and for the purpose specified.

5. The combination, in a furnace, of the fire-pot 23, the walls 25, 26, 27, and 28, having 50 the series of openings 39, and the openings 37, damper 50, steam-pipe 40, diving-flues 19, grate-bars 18, ash-box 4, draft-openings 17, and smoke-flue 33, combined and constructed substantially as described, and for the purpose specified.

In testimony whereof I have hereunto set my hand this 21st day of January, 1890.

JAMES S. HARKINS.

In presence of—

A. C. PAUL,
A. M. GASKILL.
